US00D682652S

(12) **United States Design Patent**
McRoberts et al.

(10) **Patent No.:** US D682,652 S
(45) **Date of Patent:** ** May 21, 2013

(54) **TOOL ACCESSORY HUB**

(75) Inventors: **Jason Kyle McRoberts**, Hamilton, OH (US); **Katie Nicole Lay**, Cincinnati, OH (US); **John Dale Wilson**, Liberty Township, OH (US)

(73) Assignee: **Campbell Hausfeld/Scott Fetzer Company**, Harrison, OH (US)

(**) Term: **14 Years**

(21) Appl. No.: **29/420,839**

(22) Filed: **May 14, 2012**

(51) LOC (9) Cl. **08-05**

(52) U.S. Cl.

USPC **D8/70; D8/20**

(58) **Field of Classification Search** D8/20, D8/29, 70, 86; D10/64; D15/138; D24/146; 81/121.1, 438; 125/15; 403/24, 44, 356, 403/359.1; 474/156, 162, 199; 451/342, 451/344, 351, 353, 359, 415, 442, 559; 606/171, 606/176, 178; 279/142, 145; 83/522.11, 83/697, 699.51; 30/166.3, 169, 347

(57) **CLAIM**

We claim, the ornamental design for the tool accessory hub, as shown and described.

DESCRIPTION

FIG. 1 is a perspective view of the tool accessory hub; FIG. 2 is a top plan view of the tool accessory hub of FIG. 1; FIG. 3 is an end view of the tool accessory hub of FIG. 1; and, FIG. 4 is a side elevation view of the tool accessory hub of FIG. 1, the opposite side elevational view being identical thereto.

The broken lines shown illustrate portions of the tool accessory hub that form no part of claimed design.
